Primary Examiner — Catherine Tuttle(74) *Attorney, Agent, or Firm* — Howison & Arnott, LLP(57) **CLAIM**

The ornamental design for a puzzle, as shown and described.

DESCRIPTION

FIG. 1 is a left perspective view of a puzzle showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating the portions of the puzzle that form no part of the claimed design.
